United States Patent Office

Des. 182,895
Patented May 27, 1958

182,895

PEW OR THE LIKE

Alfred C. Hoven, William S. Lindberg, and Walter E. Nordmark, Grand Rapids, Mich., assignors to American Seating Company, Grand Rapids, Mich., a corporation of New Jersey

Application May 23, 1957, Serial No. 46,308

Term of patent 14 years

(Cl. D15—11)

Fig. 1

Fig. 2

Fig. 3

Figure 1 is a front perspective view of a pew showing our new design; Figure 2 is a rear perspective view of the same; and Figure 3 is a sectional view on line 3—3 of Fig. 1.

We claim:

The ornamental design for a pew or the like, substantially as shown.

References Cited in the file of this patent

UNITED STATES PATENTS

D. 145,918 Armstrong ----- Nov. 19, 1946